UNITED STATES PATENT OFFICE.

LOUIS FRED HURD, OF NEWARK, NEW JERSEY, ASSIGNOR TO LEROY W.
FAIRCHILD & CO., OF NEW YORK, N. Y.

DESIGN FOR A MATCH-BOX.

SPECIFICATION forming part of Design No. 21,891, dated October 11, 1892.

Application filed September 7, 1892. Serial No. 445,272. Term of patent 3½ years.

To all whom it may concern:

Be it known that I, LOUIS FRED HURD, a citizen of the United States, residing at Newark, in the county of Essex and State of New Jersey, have invented and produced a new and original Design for Match-Boxes, of which the following is a specification.

My invention has reference to a new design for match-boxes, and is illustrated in the accompanying drawing, which is a face view of the box.

The sides of the box are substantially straight and parallel, and along the edges is a small neat border *a*.

The bottom of the box is formed by reversely-

curved continuations of the sides, and at the point where the curves join or come to a point is a scroll *b*.

The top is made slightly concave and joins the sides by easy curves, suitable scrolls or ornaments *c* being arranged within the corners.

What I claim is--

The design for a match-box herein described and illustrated.

In witness whereof I hereunto set my hand in the presence of two witnesses.

L. FRED HURD.

Witnesses:

N. H. McCARTER,

EDWARD W. CAMPBELL.
